THOMAS BARNES, OF WAYNE, MICHIGAN.

Letters Patent No. 92,509, dated July 13, 1869.

IMPROVEMENT IN FENCE.

The Schedule referred to in these Letters Patent and making part of the same.

To all whom it may concern:

Be it known that I, THOMAS BARNES, of Wayne, in the county of Wayne, and State of Michigan, have invented a new and useful Improvement in Fences; and I do hereby declare that the following is a full, clear, and exact description thereof, which will enable others skilled in the art to make and use the same, reference being had to the accompanying drawings, forming part of this specification.

This invention relates to improvements in fences, designed to provide a simple, cheap, and durable construction of the same, adapted either for permanent or portable fences, as hereinafter more fully specified.

Figure 1 represents a front elevation of my improved fence.

Figure 2 represents a section of the same.

Similar letters of reference indicate corresponding parts.

I support the posts A upon the transverse sills B, by forming vertical recesses in the sides of the sills, at the centre, and also slightly rebating the ends of the posts, to fit therein, when they are securely nailed and braced by braces C.

These sills are supported upon blocks or stones at each end, and bedded, to some extent, in the ground.

To prevent the sills from sliding on the said supports; they are notched, as represented at D, where they rest on the blocks, and the shoulders projecting down against the sides of the blocks.

I nail the boards to three or more strips F, having inclined slots opening downward, as represented at G, and arranged for hooking into pins or studs H, driven into the sides of the posts A, and projecting sufficiently to support the said panels when connected thereto, as represented in fig. 1.

The ends of each panel are designed to meet at the centre of the post at the said ends of the panels.

These panels may be removed from the posts at any time, to change the position of the fence very readily.

Having thus described my invention,

I claim as new, and desire to secure by Letters Patent—

The panels, provided with the inclined slots G in the transverse strips, combined with the posts, having the studs H, as specified.

THOS. BARNES.
